UNITED STATES PATENT OFFICE

ROBERT E. PELLOW, OF WACO, TEXAS

DESIGN FOR A COCKTAIL SPOON

Application filed May 23, 1931. Serial No. 39,940. Term of patent 14 years.

To all whom it may concern:

Be it known that I, ROBERT E. PELLOW, a citizen of the United States of America, residing at Waco, in the county of McLennan and State of Texas, have invented a new, original, and ornamental Design for a Cocktail Spoon, of which the following is a specification, reference being had to the accompanying drawings, forming a part thereof.

Figure 1 is a perspective view, and

Figure 2 is an edge view showing my new design.

The cocktail spoon has been illustrated in the drawings as of the relative contour and proportions of a spoon. A cross-sectional view of the handle of the spoon would illustrate the spoon as provided with the conventional type of handle.

I claim:

The ornamental design for a cocktail spoon as shown and described.

ROBERT E. PELLOW.
